UNITED STATES PATENT OFFICE.

PHILETUS WARREN GATES, OF CHICAGO, ILLINOIS, ASSIGNOR TO THE
GATES IRON WORKS, OF ILLINOIS.

AUTOMATIC FEEDER FOR STAMP-MILLS.

SPECIFICATION forming part of Letters Patent No. 609,425, dated August 23, 1898.

Application filed April 30, 1897. Serial No. 634,567. (No model.)

To all whom it may concern:

Be it known that I, PHILETUS WARREN GATES, a citizen of the United States, residing at Chicago, in the county of Cook and State of Illinois, have invented certain new and useful Improvements in Automatic Feeders for Stamp-Mills, of which the following is a specification.

The object of my invention is to provide a simple, economical, and efficient automatic feeding mechanism to be used in connection with a stamp-mill or stamp-mill batteries; and the invention consists in the features, combinations, and details of construction hereinafter described and claimed.

In the accompanying drawings, Figure 1 is a side elevation of my improvement attached to a portion of a mill; Fig. 2, a front view of the same, partly in section; Fig. 3, a plan view of the feeder with the stamp-stem and cylinder-supports shown in section and the tappet-collars shown in dotted lines; Fig. 4, a plan view of the oscillating plate, and Fig. 5 a rear view of the same.

In the art to which this invention relates it is well known that it is desirable to provide feeding mechanism for the automatic feeding of ore or other materials into the mortar of the stamp-mill, according to the quantity of the material therein—that is, if the layer of material being stamped is of minimum thickness the feeding of the material into position will be uniform and will vary until it exceeds a certain predetermined thickness, when the feeding will automatically cease until the layer falls below the predetermined thickness.

The object of my invention, therefore, is to provide a simple, economical, and efficient mechanism that will attain these results; and the invention consists in the features, combinations, and details of construction hereinafter described and claimed.

In illustrating and describing my improvement I will only illustrate and describe those portions which I consider to be new, taken in connection with so much that is old as will enable those skilled in the art to practice the same, leaving out of consideration other and well-known mechanisms, which, if described here, would only tend to confusion and ambiguity.

In constructing a machine in accordance with my improvements I make a frame portion A and secure it to the back part of the 55 mortar B in any desired manner, preferably by means of bolts and nuts b, as shown in the drawings. To hold and sustain the material to be fed into the machine, I provide a feeding oscillating plate C, which is provided 60 with a curved bottom portion c, having end portions terminating in gudgeons D, by which the plate is pivoted to and oscillated in the frame portion. This oscillating feeding-plate is further provided with an integral lever E, 65 having a projecting downward leg F.

To impart the necessary vibratory motion to the oscillating feeding-plate, a standard G is provided and secured in any desirable manner to the frame portion. In this standard I 70 pivot an actuating-lever H, which has its free end projecting under the reciprocating parts of the stamp and arranged to be contacted by a tappet-collar I, arranged on the piston-rod I' of the stamp-mill. The other end of 75 this actuating-lever is provided with a connecting-rod J, which is adjustably connected with the actuating-lever and pivotally connected at j with the lever-arm of the oscillating feeding-plate.

To normally hold the oscillating feeding-plate against the movements of the lever, or, in other words, to thrust it forward in opposition to the movements of the actuating-lever, a helical coiled spring K is provided, 85 which is pivotally secured to the lever at k and adjustably secured to the mortar by means of a tie-bolt k'. A set-screw H' is adjustably secured to some portion, preferably one of the pillars I², of the stamping-mill to 90 limit the return motion of the actuating-lever, as will be hereinafter more fully described.

To supply the oscillating feeding-plate with the proper amount of ore or other material, a 95 hopper L is provided, having side plates L' and a bottom plate L², that extends out to about the center of the curved bottom of the oscillating feeding-plate and is preferably provided at its lower end with an adjustable plate L³ for the purpose of obtaining the correct amount of clearance. The opposite or rear side of the hopper is provided with a short adjustable portion L⁴, having a handle 100

L^4 , by which the opening below the lower portion thereof, as at L^5 , may be regulated, so as to govern the amount of material fed onto the oscillating feeding-plate.

5 The operation is as follows: The hopper is filled with ore and the slide L^3 raised the desired amount, so as to allow the material to pile up on the curved plate c to the front edge or nearly so. The position of the actuating-lever is then adjusted by means of the set-screw H' , so that a minimum amount or thickness of the layer of material on the die of the mortar may be provided. The reciprocation of the piston-rod causes the tappet-collar to impinge against the actuating-lever and vibrate the feeding-plate in such a manner that material is fed over the edge c' into the mortar. As the material piles up on the mortar bed or die it will soon become so 10 thick that the stamp cannot pulverize it as fast as it is being fed in. When it reaches this point, which generally can be predetermined, the tappet-collar will cease to strike this actuating-lever, and as a consequence 15 the feeding in of the material will cease until the layer of the material on the die-bed falls below the predetermined thickness. The thickness of the layer of material on the die or mortar-bed can be regulated by adjust- 20 25

ing the tappet-collar L , so that it will strike the actuating-lever early in its movements, or the set-screw H can be moved up, so as to permit the actuating-lever to have a longer range of action.

I claim—

In an oscillating feeder for stamp-mills, the combination of an oscillating feeding-plate provided with a curved bottom portion, a hopper having its inclined bottom terminating at or about the center of the oscillating feeding-plate, gate mechanism in such hopper to regulate the flow of material to such oscillating feeding-plate, an actuating-lever adjustably connected with the oscillating feeding-plate and having its free end arranged under a movable part of the stamp, spring mechanism for thrusting forward the oscillating feeding-plate in opposition to the movements of the actuating-lever, an adjustable tappet-collar on a movable part of the stamp arranged to contact the actuating-lever, and an adjustable set-screw to limit the range of action of the actuating-lever, substantially as described.

PHILETUS WARREN GATES.
